UNITED STATES PATENT OFFICE.

GEORGE L. ABBOTT, OF CORNING, NEW YORK.

DESIGN FOR A GLASS DISH.

SPECIFICATION forming part of Design No. 17,110, dated February 15, 1887.

Application filed December 29, 1886. Serial No. 222,844. Term of patent 3½ years.

To all whom it may concern:

Be it known that I, GEORGE L. ABBOTT, a citizen of the United States, residing at Corning, in the county of Steuben and State of New York, have invented and produced a new and original Design for Glass Dishes and Vessels; and I do declare the following to be a full, clear, and exact description of the same, reference being had to the accompanying drawings, forming a part thereof.

Figure 1 represents a panel containing my new design for the ornamentation of glass dishes and vessels; and Fig. 2 is a sectional view thereof, showing the relief formation of that part of the surface of the article containing my new design.

In the drawings, the letter A indicates a panel or figure formed in relief upon the surface of the dish or article to be ornamented, and these figures or panels are symmetrically disposed upon the body of the article to suit the character of the latter. The ornamentation consists, essentially, of a sixteen-pointed star surrounded by groups of pyramidal and diamond-shaped blocks or formations or figures terminating in a border of fan-shaped points, which are preferably disposed so as to form the angles of the panel which forms the design. The sixteen-pointed star B is formed within a square or quadrangular figure, C, the border whereof is preferably a rectangular figure, D, and contains triangular pyramids or quarter-diamonds E, block diamonds F, and

diamonds G. The block diamonds or figures have surface radial lines, while the diamonds have surface cross-lines and are arranged upon each side of fan-shaped figures H, which form the points or angles of the panel.

The design in relief has a uniform surface prominence.

The leading feature of my design consists of a panel having a surface ornamentation formed in relief having a uniform projection consisting of a sixteen-pointed star, the points whereof are bounded by block and diamond shaped formations pointed with spread fans, between which and surrounding the central star-pointed figure the diamond formations are continually repeated.

I claim—

The design for the ornamentation of glass dishes and vessels herein shown and described, the same consisting of a quadrangular figure containing a centrally-located sixteen-pointed star, the points whereof terminate in quarter and block diamonds, the latter having radial line surfaces, and diamonds having surfaces of crossed lines terminating at the border of the design.

In testimony whereof I affix my signature in presence of two witnesses.

GEORGE L. ABBOTT.
